schaft, Siemensstadt, near Berlin, Germany

Application April 30, 1932, Serial No. 608,401, and
in Germany May 5, 1931

13 Claims. (Cl. 179—27)

This invention relates to multi-office telephone systems in general and more particularly to systems of this type in which certain classes of connections are established under control of the calling subscriber while other classes of calls are completed by a manual operator. The object of the invention is the provision of new and improved circuits and apparatus for enabling the operators in such systems to extend and supervise connections with the greatest efficiency.

The invention is particularly adapted for use in systems in which the subscribers' lines are equipped with automatic charging devices and in which the operation of the device is determined by the particular office or zone to which a connection is extended. The apparatus for controlling the operation of the charging devices is preferably set by the calling subscribers before the connections are extended to the operator. The setting may be accomplished by a calling subscriber dialling a digit or digits indicating the route or value of the connection as determined by the office or zone for which the call is intended. This arrangement relieves the operator of the necessity of setting the controlling apparatus or of controlling the charge devices manually. In prior systems, however, it has been necessary for the operator to check the setting of the control apparatus in order to insure the assessment of the proper charge for a call.

The present invention further simplifies the operator's duties by providing an automatic check on the setting of the control apparatus. An automatically controlled signal at the operator's position is arranged to indicate any discrepancy between the value of a connection as requested by the calling party and the value of the connection as finally established by the operator. If given the facilities provided by the present invention, the operator need not trouble to check whether the value of the connection required by the calling subscriber equals the value of a connection in the indicated zone. If she does not receive the signal immediately after having performed the required switching operations (i. e., seized an outgoing line) she knows at once that the subscriber has either made a mistake or has fraudulent intent. A fraud may be suspected when, for example, the digit denoting a connection of low value is dialled and a corresponding low fee is charged and the subscriber then requires a connection of high value. The operator is consequently in a position to refuse the further setting up of the connection.

Operators are also given the facility of being

able to determine at a glance whether a connection has been set up, the value of which does not correspond to the value of the connection in the indicated traffic zone.

The signal lamp associated with the incoming line may also be suitably controlled by the switching devices.

One embodiment of the invention is shown in the accompanying drawing. Only the switching apparatus and circuit details necessary for explaining the subject matter of the invention have been shown. This includes an incoming trunk terminating in a jack AK, an operator's cord circuit, a number of trunks outgoing to different offices from the operator's position Fig. 1, and call-checking equipment AS. The multiple connections of the outgoing trunk at a second operator's position Fig. 2 have also been shown.

The devices at the operator's position Fig. 1 are seized over the c-lead over which the following circuit is closed: earth applied by the preceding connecting device, c-lead winding of relay C, contacts 304c, 306g, battery, earth. A number of groups of incoming lines lead to the operator's position and each line is associated with an indicator comprising a stepping switch which operates after the manner of a call finder and is represented for convenience as a call finder AS, a switch W, and a signal lamp. Relay C is energized in the above-mentioned circuit and sets up its own locking circuit by closing its contact 305c (light contact). The following circuit for relay G is completed at contact 313c: earth, contacts 312tr, 313c, winding of relay G, battery, earth. Relay G is energized in this circuit and opens its contact 306g. This disconnects battery, with the result that other incoming lines of this group cannot seize the device at the operator's position. Relay C has also closed its contact 322c and thus completed the following circuit: earth, contacts 321tr, 322c, winding of relay An, contact 323p, battery, earth. Relay An closes its contact 320an and consequently also the stepping circuit for the call finder AS: earth, interrupter U2, contact 319p, magnet Das, contact 320an, battery, earth. The magnet Das, under the influence of the interrupter U2, advances its switch wipers a, b, c, d, step by step. When the switch wiper a has reached the contact in the call finder AS to which earth is applied at contact 308c, the following circuit will be set up: earth, contacts 307tr, 308c, a-wiper of the call finder AS, windings I and II of relay P, contact 311f, battery, earth. Relay P is energized in this circuit. The high resistance wind-

ing II of relay P is short circuited by the closing of contact 310p so as to set up the guarding against further seizures. A locking circuit for relay P is set up independent of contact 307tr due to the closing of contact 309p. The opening of contact 319p cuts off the stepping circuit for the call finder AS with the result that said switch is brought to rest. Due to the opening of contact 323p the circuit for relay An is opened at 10 the same time and this relay, by opening the contact 320an, opens a second point in the circuit for the driving magnet.

The calling subscriber, after having received a signal (not shown in the drawing) which may be transmitted to him over a front contact of relay C, now sends out an impulse series denoting the traffic zone. Relay A is influenced by said impulse series over the *a*-lead. The impulses actuating relay A are transmitted at contact 20 317a to the rotary magnet Dw of the switch W. Said rotary magnet is energized in the following circuit: earth, contacts 317a, 318c, *b*-wiper of the call finder AS, winding of the rotary magnet Dw, winding of relay V, battery, earth. The wipers *aw* and *bw* of the switch W are set to a definite contact according to the number of impulse series. It will be assumed that the impulse series consists of a single impulse and that therefore the wipers of the switch W are set 30 to the first contact. The slow-acting relay V is disposed in the stepping circuit and is adapted to disconnect the signal lamps during the setting operation by opening its contact 360v. The following circuit is set up when contact 360v has been closed after a definite period following the last impulse of the transmitted impulse series: earth, contacts 324f, 360v, wiper *aw* of the switch W, lamp L1, battery, earth. The lamp L1 therefore lights up and characterizes a definite traffic zone, for example, zone 1 in which zone the calling subscriber required a connection. On the release of relay V and after contact 326v has been closed, the following circuit is completed for the signal lamp AL: earth, signal lamp AL, *c*-wiper of the call finder AS, contacts 326v, 327kw (off normal contact, which is mechanically closed on the first step executed by the switch W) contact 328f, battery, earth. An additional contact 314kw, which is mechanically actuated by the stepping switch on its advance maintains the 40 circuit for relay G independent of contact 312tr. The lighting of the signal lamp AL indicates to the operator that a subscriber is calling, whereupon she inserts the answering plug ASt into the jack AK. The following circuit is now set up over the plug sleeve: earth, supervisory lamp SL, plug sleeve of the plug AK, winding of relay Tr, contact 303c, resistance Wi1, battery, earth. Relay Tr is energized in this circuit, whereas the supervisory lamp SL cannot light due to the resistance Wi1 placed in this circuit. Relay Tr, at contact 60 321tr, opens an additional point in the circuit for relay An, and also a point in the circuit for relay G at contact 312tr. The impulse relay A is disconnected at contact 301tr, while the circuit closed for the purpose of energizing relay P is opened at contact 307tr. Relay P, however, as already mentioned, cannot yet relapse due to the fact that contact 309p has closed a locking circuit 65 for it. The operator, after having received the calling subscriber's instructions, inserts the calling plug VSt in a jack to which a junction line leading to the required exchange is connected. Previous to this, however, she tested in known manner, for example, by the known click test,

whether the junction line in question is idle or busy. Assuming that the outgoing junction line connected to the jack Ka1 and leading to the exchange required by the calling subscriber is idle, the operator, on inserting the plug VSt in the jack Ka1, completes a circuit for relay HR which was preparatorily connected up on the insertion of the enquiry plug ASt: earth, resistance Wi2, plug sleeve of the jack Ka1, line in the cord circuit, corresponding contact spring, winding of relay HR, battery, earth. Relay HR is energized in this circuit, closes its contact 329hr and thereby sets up the following circuit for relay F: earth, contact 329hr, *d*-wiper of the call finder AS, winding of relay F, *bw*-wiper of the switch W, contact 1, contacts 332lr1, 333e1, battery, earth. Contact 332lr1 was closed when the plug was inserted in the jack KA1 due to the fact that the following circuit was completed for relay LR1: earth, contact spring 346, winding of relay LR1, battery, earth. Relay LR1, in addition to closing contact 332lr1, also closes its contact 338lr1 and consequently the following circuit for relay E1: earth, contact 338lr1, winding of relay E1, battery, earth. Relay E1 is so constructed that it actuates its contact only after a definite period. Relay F is energized in the above circuit as long as the contact 333e1 is closed in addition to contact 332lr1.

Relay F, as will be more fully explained below, can only be energized when the seized junction line leads to the traffic zone denoted by the switch W which is set by the identification digit. Said relay F opens its contact 324f and consequently also the circuit which caused the zone indicating lamp to be lighted. When the lamp is extinguished, the operator knows that the traffic zone dialled by the calling subscriber co-incides with the zone denoted by the switch W. The signal lamp AL is extinguished at the same time due to the opening of contact 328f. The opening of contact 311f cuts off the locking circuit for relay P with the result that this relay releases. The opening of contact 309p prevents relay P from being connected up afresh on the release of relay F. The closing of contact 315p sets up the stepping circuit for the rotary magnet DW of the switch W as follows: earth, interrupter U1, contacts 315p, 316kas (closed as soon as the call finder leaves its normal position) winding of the stepping magnet W, winding of relay V, battery, earth. The interrupter U1 causes the wipers *aw* and *bw* of the switch W to advance step by step until they reach their original positions in which contact 316kas and consequently the above-mentioned stepping circuit is opened. Due to relay V being re-energized, which caused the opening of contact 360v, the lamps cannot be lighted while the switch W is being restored to normal. The circuit for relay F is only maintained for a short period but of sufficient duration to restore the switch W to normal by opening contact 311f. The circuit for relay F is cut off at contact 333e1 when relay E1 is energized after a short period. As soon as the switch W has reached its original position, contact 314kw will be re-opened, causing relay G to release. This results in the closing of contact 306g, whereupon the indicator may be seized by other incoming lines of the group.

Four outgoing junction lines are shown in the drawing, each two of which are of the same value. Thus the junction line connected to the jack Ka2 leads to the same traffic zone as the line connected to the jack Ka1. If, for example, the junction line connected to the jack Ka1 is seized from an-

other operator's position, the operator at position API, upon finding this line test busy, will insert the plug VST in the jack KA2. Relay LR2 is then energized, closes its contact 330lr2 and, when the switch W is set as before, closes a circuit for relay F which extends over contact 331e2. Apart from this, all the remaining switching operations are identical with those previously described.

Should the switch W be set to a different contact, for example, contact 2 due to the transmission of a different identification digit, relay F can only be energized over the contacts associated with relays LR11 and LR12; that is to say, when a connection is to be set up over the outgoing lines connected to the jacks KB1 and KB2. The devices associated with these jacks are exactly identical with those associated with the jacks KA1 and KA2. Either relay LR11 or LR12 is energized according to whether the plug is inserted in the jack KB1 or KB2. The circuit for relay F is accordingly closed over either contact 334lr11 or 336lr12 and also over either contact 335e11 or 337e12.

If the calling subscriber now requests the operator to complete a connection the value of which differs from that denoted by the switch W according to the identification digit, a circuit for relay F cannot be set up on the insertion of the plug in the jack to which the required junction line is connected due to the fact that the corresponding contacts of relay LR are not connected over the bank contact to which the switch W has been set. Relay F, therefore, cannot be actuated with the consequence that the zone indicating lamp is not extinguished. This gives the operator to understand that the calling subscriber either has made a mistake or else is endeavoring to put through a fraudulent call. The operator therefore immediately breaks the connection, informs the subscriber accordingly, and requests him to adjust the discrepancy.

When at the end of the conversation, the calling subscriber transmits the clearing signal, relay C is the first to release. Contact 302c is therefore closed and the resistance W11 is disconnected. The current passing through the supervisory lamp SL is then increased to such an extent that this lamp will be lighted. The operator is thus informed that the conversation has ended and consequently withdraws the calling and answering plugs from their respective jacks which causes all the associated devices, including relays LR and E, to be restored to normal.

As previously mentioned, a plurality of groups of incoming lines may terminate at an operator's position, each line being associated with an indicator. Relays LR and E in a connection of the type described above then actuate the indicators of all the other groups, that is to say, either contacts 330lr2, 332lr1, or contacts 334lr11 are actuated. The circuit for relay F in the other indicators, however, cannot be closed owing to the energization of this relay being dependent on relay HR, individually associated with each incoming line.

The drawing also shows a second operator's position AP2 provided with corresponding indicators not shown in the drawing. Connections may be set up over the same outgoing lines also from this operator's position. The indicators at the operator's position AP1, however, cannot be influenced when the operator at the position AP2 seizes the lines or vice versa due to the fact that the switching means which influence the indicators (relays LR and E) are arranged

individually for each operator's position and are only operable on the setting up of connections from the appropriate operator's position. Thus the common outgoing junction lines for the operator's position Fig. 2 are connected to the jacks KA1', KA2', KB1' and KB2'. The relays which are influenced on the setting up of connections and which actuate the indicators (not shown) at the operator's position Fig. 2, in this case are represented by the reference characters LR1', LR2', LR11', and LR12'. Apart from this the switching operations carried out for the setting up of connections from the operator's position Fig. 2 are exactly identical with those already described.

What is claimed is:

1. In a telephone system in which the value of a connection is indicated by a calling party prior to the extension of the connection, means including a cord circuit for extending the connection, and a signal operated responsive to the extension of a connection of a different value than that indicated by the calling party.

2. In a telephone system in which a calling party first indicates the value of a wanted connection and is then connected to an operator's position, means at the position for completing connections of different values, and means at the position for notifying the operator when the value of a completed connection differs from the value indicated by the calling party.

3. In a telephone system in which a calling party first indicates the zone to which a connection is desired and is then connected to an operator's position, means at the position for extending the connection to any one of a plurality of zones, and a signal at the position for notifying the operator whether the connection has been extended to the zone indicated by the calling party or to a different zone.

4. In a multi-office telephone system in which a calling party in one office to obtain connection with a called party in a different office first registers the designation of the wanted office to obtain a connection with an operator's position, means at the position for extending the connection to any one of a plurality of offices, and means at the position operated responsive to the extension of the connection for indicating that the connection has been extended to the office designated by the calling party.

5. In a telephone system in which a calling party initially indicates the value of a desired connection and is then connected to an operator's position, a signal at the position operated responsive to a call of any value, means at the position for further extending the connection, and means operated when the value of the extended connection corresponds with the indicated value of the wanted connection for disabling said signal.

6. In a telephone system in which a calling party initially indicates the trunk to which a connection is desired and is then connected to an operator's position, a signal at the position operated responsive to the call and independent of said trunk indication, means at the position for connecting the calling party to any one of a plurality of trunks, and means associated with the trunks for disabling said signal when the trunk connected corresponds to the trunk indicated by the calling party.

7. A telephone system as claimed in claim 6 in which the means associated with the trunks consists of a pair of relays for each trunk and circuit

- connections controlled by the relays for disabling the signal.

8. In a telephone system, an operator's position, an incoming trunk terminating at the position, a plurality of groups of outgoing trunks terminating at the position, cord circuits for connecting said incoming trunk to any one of said outgoing trunks, checking apparatus comprising two switches, means for extending a connection to said position via said incoming trunk, means responsive to the extension of the connection for causing the first of said switches to associate itself with the trunk, means responsive to impulses received over the incoming trunk for setting the other of said switches to indicate a particular group of outgoing trunks, and means responsive to the connection of the incoming trunk to an outgoing trunk in the group indicated for releasing said other switch.

9. A telephone system as claimed in claim 8 in which the two switches jointly control a signal for notifying the operator that the outgoing trunk connected with is in the group indicated by the digit impulses received over the incoming trunk.

10. In a telephone system, a trunk line extending to an operator's position, means including an automatic switch responsive to a digit called by a subscriber for connecting his line to said trunk line, a register switch associated with the position for recording a further digit which is characteristic of the desired connection, means whereby the operator can answer the call and complete a connection requested by the subscriber, and means for notifying the operator in case the connection completed does not correspond to the one denoted by the setting of said register.

11. In a telephone system, an operator's switch-board, means for extending a calling line thereto, means for requiring the calling subscriber to dial a digit indicative of the connection desired before the operator is signalled, means for completing any connection requested by the subscriber, and means for notifying the operator if there is a discrepancy between the connection indicated by the dialled digit and the one actually requested by the subscriber and completed by the operator.

12. In a telephone system, a trunk line incoming to an operator's position, means for extending a calling line to said trunk line, a plurality of trunks outgoing from said position, a verification switch which is set by the calling subscriber over the said incoming trunk in accordance with a desired outgoing trunk, means whereby the operator can connect the incoming trunk with any outgoing trunk requested by the subscriber, and means for advising the operator of the fact when she connects up an outgoing trunk which does not correspond with the setting of said switch.

13. In a telephone system, a trunk line incoming to an operator's position, means for extending a calling line to said trunk line, a plurality of trunks outgoing from said position, a verification switch which is set by the calling subscriber over the said incoming trunk in accordance with a desired outgoing trunk, means whereby the operator can connect the incoming trunk with any outgoing trunk requested by the subscriber, a trunk signal actuated by said switch, and means responsive to the connecting up of an outgoing trunk which corresponds to the signal for releasing the switch and restoring the signal.
